The schedule referred to in these Letter Patent and making part of the same.

To all whom it may concern:

Be it known that I, H. G. Thompson of the City, County and State of New York, have invented or produced a new and original Design for a Pattern to be wrought into 2-ply, Ingrain and other Carpeting, in colors similar to those painted on the drawings accompanying this specification, or in other colors substituted in the places of those painted on the drawings.

herewith, and I solemnly declare that the drawings accompanying this specification do give and convey to any one skilled in the art of carpet weaving a more defined and thorough description of the nature of my invention than it is in the power of language to convey, and is sufficient to enable any one skilled in the art of carpet weaving to use my invention.

What I claim as my invention and desire to secure, by Letters Patent, is the configuration of the Design, as now specified, when made by being wrought into 2-ply, Ingrain or other carpeting, in the form similar to the drawings accompanying this specification.
